UTILITY TRAY

Louise B. Haley, Middletown, N. Y.

Application December 14, 1940, Serial No. 370,222

1 Claim. (Cl. 155—123)

The present invention relates to new and useful improvements in utility trays for use particularly by beauty operators and has for its primary object to provide, in a manner as hereinafter set forth, novel means whereby the device may be expeditiously and firmly secured in position on different types of chairs.

Another very important object of the invention is to provide a tray of the aforementioned character which is adapted to hold conveniently at hand substantially all of the various articles, products, appliances, etc., which the operator may wish to use.

Other objects of the invention are to provide a tray of the character described which will be comparatively simple in construction, strong, durable, highly efficient and reliable in use, compact, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of an embodiment of the device.

Figure 2 is a view in rear elevation thereof.

Figure 3 is a vertical sectional view, taken substantially on the line 3—3 of Figure 1.

Figure 4 is a bottom plan view of the tray.

Figure 5 is a fragmentary view in vertical section, taken substantially on the line 5—5 of Figure 4.

Figure 6 is a view in rear elevation, showing the supporting means adjusted for mounting on a shampoo chair, the lower portion of said supporting means being broken away.

Figure 7 is a view in side elevation, showing the invention ready to be mounted on a shampoo chair.

Referring now to the drawing in detail, it will be seen that the embodiment of the invention which has been illustrated comprises an elongated shallow pan or tray 1 which, of course, may be of any suitable material. In plan, the tray 1 is of substantially the shape shown to advantage in Figure 4 of the drawings.

The tray 1 is adapted to be removably mounted on top of the back 2 of a chair of the low type. Toward this end, the tray 1 has secured to its bottom 3 a pair of depending hooks 4. It will be observed that the hooks 4 are located adjacent the sides or ends of the tray 1 at the

front thereof. The hooks 4 are engageable with the front of the chair back 2. Rubber protectors 5 for the chair are provided on the hooks 4.

The attaching means for the tray 1 further includes a stationary base plate 6 which is rigidly secured in any suitable manner to the bottom 3 of said tray. Depending from the base plate 6 is a threaded shank or bolt 7. Rotatably and slidably mounted on the plate 6 is an adjustable metallic bar 8 having a longitudinal slot 9 therein through which the bolt 7 passes. A wing nut 10 is threaded on the bolt 7 for frictionally securing the bar 8 in adjusted position.

15 The reference numeral 11 designates a metallic supporting post which is pivotally mounted for swinging adjustment on one end portion of the bar 8 through a hinge connection 12. Adjustably and removably mounted on the lower 20 end portion of the supporting post 11 is a foot 13 comprising a cushion or pad 14 which is engageable with the chair back 2 in the manner shown to advantage in Figure 3 of the drawings.

The tray 1 is adapted to receive a removable 25 container which is designated generally by the reference numeral 15. The container 15 conforms in shape to the tray 1 and has formed therein an elongated receptacle 16. The receptacle 16 is divided by partitions 17 (see Figure 30 3) into compartments for the reception of various articles. A slidably mounted cover 18 closes a portion of the receptacle 16 and permits access to be readily had to the desired compartments therein. Additional receptacles 20 are provided 35 in the container 15 at the ends of the main receptacle 16.

In use, the tray 1 is mounted on top of the chair back 2 with the hooks 4 engaged over the front of said chair back. The foot 13 of the adjustable supporting post 11 bears against the back 2 and in this manner the tray is firmly but removably held in position. Any desired adjustment that may be necessary can be conveniently had by simply loosening the wing nut 21 of the hinge joint or connection 12. The tray 1 45 may be used by itself for the reception of various articles or products. When the devices or articles in the container 15 are desired, said container is simply placed in the tray 1.

50 When the device is to be mounted on a shampoo chair the wing nut 10 is loosened and the bar 8 is swung forwardly to the position shown in Figure 7 of the drawings on the bolt 7. The slot 9, as hereinbefore mentioned, also permits longitudinal adjustment of the bar 8 with the

post 11 thereon. The foot 13 is removed and the post 11 is inserted in the receptacle (not shown) which is ordinarily provided on the back of a shampoo chair for attaching a shampoo tray thereto. The usual thumb screw of this receptacle is then tightened for clamping the post 11 in adjusted position. The post 11 has formed in one side thereof a series of spaced depressions or sockets 22 which receive this thumb screw.

It is believed that the many advantages of a tray constructed in accordance with the present invention will be readily understood and although a preferred embodiment of the device is as illustrated and described, it is to be understood that changes in the details of construction and in the combination and arrangement of

parts may be resorted to which will fall within the scope of the invention as claimed.

What is claimed is:

A chair attachment comprising a tray, and means for removably holding said tray on the back of a chair, said means including hooks depending from the tray and engageable with the front of the chair back, a member mounted for horizontal swinging and sliding adjustment on the underside of the tray, and a post hingedly connected to said member and engaging at its lower end the rear face of the back said swingable and slidale member permitting the post to be positioned so that it may be mounted in a receptacle in the back of a chair.

LOUISE B. HALEY.
